UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,342,902.

Specification of Letters Patent. Patented June 8, 1920.

Application filed September 14, 1917. Serial No. 191,364.

To all whom it may concern:

Be it known that I, CHARLES L. GOODRUM, a citizen of the United States, residing at New York, in the county of New York and 5 State of New York, have invented certain new and useful Improvements in Telephone Systems, of which the following is a full, clear, concise, and exact description.

This invention relates to telephone systems wherein connections between subscribers' lines are effected by automatic switching mechanism.

More particularly it is concerned with certain improvements in the arrangement 15 and mode of operation of the selective switches employed in such a system.

In selector switches of the long and short step type the primary set of impulses operates to give the brush shaft a number of 20 long steps to select a desired group of trunk terminals, and in the second or trunk hunting movement of the switch the brush shaft takes a series of short steps to wipe its brushes over the terminals of the selected 25 group in search of an idle trunk. Selective switches of this character have been constructed so as to use two sets of brushes, one set of which is designed to coöperate with half of the groups of terminals, and 30 the other set to coöperate with the remaining groups. The different groups of trunk terminals are arranged in the switch with respect to their numerical designation in such a manner that the primary or direc-

35 tive series of impulses sent out by the calling subscriber serves to place the shaft with one or the other of said sets of brushes in operative relation to the particular group of trunks which have access through suc- 40 ceeding switches and apparatus to the group of lines containing the desired subscriber's line. Obviously, the amount of primary motion given the brush shaft depends upon the number of impulses sent into the switch, 45 and the particular set of brushes so positioned in operative relation to the selected group of trunk terminals is the set that is to be used in extending the connection through an idle trunk in such group. Since 50 half of the terminal groups are served by one brush set and the remaining half served by the other set, a convenient manner of dividing the groups is to arrange them in accordance with their numerical designation. That is, the odd digit groups are

served by one set of brushes and the even digit groups by the other set.

Inasmuch as both sets of brushes are carried on the same shaft and moved together under the control of the same actuating mechanism, it is desirable that provision be made whereby the particular set of brushes taken for use, in the extension of a telephone connection through such switch, be electrically associated with the calling or 60 incoming line to the exclusion of the other brush set. As seen above the set of brushes to be used is determined by the number of the primary impulses sent to the switch. In other words the brush selection, as well 65 70 as the group selection, depends upon whether the number of impulses in said series be odd or even.

The principal object of the invention is an arrangement of the controlling circuits 75 of the switch wherein the side-switch escapement magnet is capable of discriminating between an odd and an even number of impulses to effect a selection of either one or the other of the brush sets.

In the following description reference is made to the drawing forming a part of this specification, wherein the figure diagrammatically illustrates a portion of a telephone system employing a selector switch 85 of the aforementioned character, and in which are embodied the features of the present invention.

Before going into a discussion of the circuit operations involved in making a connection, a brief description will be given of the general arrangement of the selector parts. The shaft 11 is provided with a double ratchet member 12 having on one side thereof a series of closely spaced ratchet teeth 13, 90 and on the other side a series of more remotely spaced teeth 14. Securely fastened to the upper end of the shaft 11 are two sets of brushes 15, 16, 17 and 18, 19, 20. The trunk terminal bank is divided into two sec- 95 tions as shown in the figure, the odd groups of trunks being placed in the upper section and the even groups appearing in the lower one. Brushes 15, 16 and 17 are designed to wipe over the terminals of all odd groups, 100 and brushes 18, 19 and 20 over the terminals of all even groups. While only two groups and a portion of another are shown to a section it is obvious that as many groups as desirable may be provided. Fixed 110

to the lower portion of shaft 11 is a brush 21 adapted to engage the projections 22 of a stationary strip 23 for a purpose hereinafter more fully explained.

5 The primary or group selecting magnet 24 has an armature 25 pivoted at 26 and is provided at its free end with a pawl 27. Pawl 27 serves, when actuated by the stepping magnet 24, to engage one of the ratchet teeth 14, for the purpose of raising the shaft one long or group selecting step. To this end the armature 25 is made long so as to be capable of a comparatively wide range of motion. The secondary magnet 28, which 10 serves to impart to the shaft 11 a series of short or trunk-hunting steps, is provided with an armature 29 pivoted at 30, and a pawl 31 arranged to engage the ratchet teeth 13. A pawl 32 normally rests in engagement with ratchet teeth 13 to hold the shaft in whatever position it may be raised to by stepping magnets 24 and 28. Said pawl is pivotally secured to the armature 33 of release magnet 34, and is withdrawn by this 15 magnet when energized, to allow the brush shaft to restore to normal. The ratchet teeth 14 are so spaced that one long step of the shaft places the brushes 15, 16 and 17 immediately below the first group of terminals in the odd digit section, which, in a 20 1,000-line system, is the first hundred group. Two steps of the primary magnet elevate the shaft to position the brushes 18, 19 and 20 in operative relation to the first group in 25 the even digit section which group corresponds to the second hundred. If three steps are taken, brushes 15, 16 and 17 are placed just below the second group in the odd section, which is the third hundred 30 group. And likewise throughout the range of the brush shaft, if an odd number of impulses is sent to magnet 24, brushes 15, 16 and 17 will be moved into operative relation to the corresponding group of terminals in 35 the odd section of the bank, whereas if an even number is sent, brushes 18, 19 and 20 are positioned just below the corresponding group in the even section.

A description will now be given of the 50 method of extending a connection from the subscriber's substation, shown at the left of the figure, to any desired trunk group appearing in the terminal bank of the selector switch. Upon the removal of the receiver 55 at the substation, conventionally shown at 1, a circuit is completed to effect the operation of an idle finder or other preliminary switch. Such switch immediately positions its brushes 2 and 3 upon the terminals 4 and 5 respectively of the calling line, thereby completing a circuit through to the selector switch. This circuit includes the line relay 6 and is traceable from free pole of battery, left-hand winding of relay 6, first position 60 contact and side-switch wiper 7, finder

brush 3, terminal 5, over the loop of substation 1, terminal 4, finder brush 2, side-switch wiper 8 and its first position contact right-hand winding of relay 6 to ground. Relay 6 attracts its armature and establishes 70 a circuit from ground, armature and front contact of relay 6, winding of relay 9 to battery and ground. The above described operations take place in a very short space of time, and without any effort on the subscriber's part other than removing the receiver from its hook.

The sending dial 10 is now manipulated to transmit a series of impulses corresponding in number to the first digit of the called party's telephone number. For example, we will assume this system to be a 1,000-line system. In such a case only first-selector switches are necessary, and with the customary division of trunks on a decimal basis, 85 each trunk group at the selector connects with a particular hundred group of subscriber's lines. The function of the first set of impulses is then to operate the relay 6 a corresponding number of times, whereby 90 through the agency of other mechanisms hereinafter to be considered, the selector switch shaft is elevated to place one of its brush sets immediately below the desired group of trunk terminals.

95 Let it be assumed for the purpose of illustration that the number of the desired line has 5 as its first digit. The relay 6 having its above traced circuit interrupted five times, vibrates its armature correspondingly. At each retraction of its armature, a circuit is established for magnet 24 as follows: ground, armature and back contact of relay 6, conductor 35, side-switch wiper 36 and its 100 first position contact, winding of magnet 24, to the free pole of battery. Relay 9 is slow to release and does not retract its armature between impulses. In response to the closure of this circuit, the magnet 24 elevates the 105 shaft 11 five long steps, and brings the brushes 15, 16 and 17 to a position just below the third group of terminals in the odd section. This is the fifth hundred group, only a portion being shown in the drawing.

110 Upon the first retraction of the armature of relay 6, a circuit is completed for the slow release relay 37 from ground, armature and back contact of relay 6, armature and front contact of relay 9, winding of relay 37 to the free pole of battery. Relay 37 attracts its armature and closes a circuit for the escape magnet 38, traceable from ground, armature and contact of relay 37, first position contact and side-switch wiper 39, 115 conductor 40, winding of escape magnet 38, to battery and ground. The escape magnet is designed so as to step the side switch from the first to the second positions upon de-energization. At the cessation of the first 120

125

or group selecting set of impulses the line relay 6 maintains its armature attracted for a sufficient time to permit slow release relay 37 to retract its armature, and thereby interrupt the circuit of magnet 38. The side switch is thus moved into its second position where a circuit is completed for the secondary stepping magnet 28. This circuit may be traced from the free pole of battery, 5 winding of magnet 28, interrupter contacts 41, 42, conductor 43, second position contact and side-switch wiper 44, contact and right-hand armature of escape magnet 38, to ground. The interrupter contacts 41 and 10 42 are arranged to be opened by the armature 29 each time magnet 28 is energized. When the magnet 28 energizes, and thereby 15 interrupts its own circuit, pawl 31 is actuated to step brushes 15, 16 and 17 over the terminals of the selected group in search of 20 an idle trunk. Idle trunks are those upon whose test terminal a ground potential exists.

Assume that the trunk 45, 46, 47 is the first 25 idle trunk encountered in the group. When the test brush 15 steps onto the test terminal of this trunk a circuit is completed for the escape magnet 38, traceable from the grounded test conductor 45, brush 15, conductor 30 48, second position contact and side-switch wiper 39, conductor 40, winding of escape magnet 38 to battery, and ground. Magnet 38 is designed to step the side switch from the second to the third positions upon 35 its energization. As soon as the above traced circuit is closed, the escape magnet energizes and the side switch goes into position 3, thereby opening the circuit of stepping magnet 28 and arresting the movement 40 of brushes 15, 16 and 17 upon the terminals of the idle trunk 45, 46, 47. At the same time the calling line is extended by the side-switch wipers 7 and 8 to conductors 49 and 50, line brushes 16 and 17, and thence to the 45 trunk conductors 46 and 47. In a manner similar to that just described, if any other odd series of impulses is sent to the switch, brushes 15, 16 and 17 are moved into operative relation to the corresponding odd group 50 of terminals, and subsequently electrically associated with the calling line. At the end of the conversation, the calling subscriber by hanging up his receiver causes a ground to be placed upon the test terminal of the trunk 55 45, 46, 47 in any suitable manner. A circuit is then traceable from grounded trunk conductor 45, test wiper 15, conductor 48, third position contact and side-switch wiper 51, off-normal contacts 54, winding of release magnet 34, to battery and ground. Magnet 34 by attracting its armature withdraws the holding pawl 32 from ratchet teeth 13 to permit a restoration of the brush shaft to normal. At the same time it closes 60 a locking circuit for itself at the spring con-

tacts 52 and 53, which circuit leads from free pole of battery, winding of magnet 34, off-normal contacts 54, contacts 53 and 52, to ground.

We will now follow the operation of the 70 switch when the subscriber at substation 1 wishes to place himself in communication with a subscriber whose line designation is a number having an even first digit, as for instance, the digit 6. Such a line is represented 75 at the selector switch by the sixth hundred group of trunks, which is therefore, the third group in the lower or even digit section of the bank.

Upon the calling subscriber manipulating 80 the sending dial 10 to transmit a series of six impulses, line relay 6 vibrates its armature as before and causes the magnet 24 to elevate shaft 11 six long steps. This time the brushes 18, 19 and 20 are positioned below the desired group of trunk terminals. Also the brush 21, hereinbefore referred to, 85 is brought to rest upon one of the projections 22 of conducting strip 23, namely, the third projection from the bottom. Strip 23 is 90 connected by conductor 55 to a contact lever 56, mounted on a friction pivot 57, and arranged to engage a grounded contact 58, when in the position shown in the figure. Armature 29 of the secondary magnet carries 95 an upwardly extending pin 59 designed to engage lever 56 and tilt it up out of contact with 58 upon the first actuation of said armature. The friction of its pivoted support is sufficient to hold the lever 56 in such 100 position until the shaft is again restored to normal, at which time a finger 60 moves it back into engagement with grounded contact 58.

When the series of group selecting impulses ceases and relay 6 retains its armature attracted, slow release relay 37 deenergizes and permits escape magnet 38 to pass the side switch from the first to the second positions in the manner previously explained. A new circuit is thereupon immediately established for the escape magnet leading from free pole of battery, winding of magnet 38, side-switch wiper 61 and its second position contact, back contact and left-hand armature of magnet 38, conductor 62, brush 21, projection 22, conductor 55 to ground at lever 56 and contact 58. The escape magnet energizes and steps the side switch to position 3 before the secondary magnet has had time to operate. In position 3 of the side switch a circuit is again completed for the escape magnet as follows: free pole of battery, winding of magnet 38, side-switch wiper 61 and its third position 110 contact, to ground over the path above traced. By attracting its left-hand armature, magnet 38 interrupts its own circuit and upon deenergization passes the side switch into the fourth position. A circuit 115 120 125 130

is now closed for stepping magnet 28 leading from free pole of battery, winding of magnet 28, interrupter contacts 41 and 42, conductor 43, fourth position contact and 5 side-switch wiper 44, to ground at the contact and right-hand armature of magnet 38. Stepping magnet 28 elevates the shaft step by step to trail the brushes 18, 19 and 20 over the trunk terminals of the selected group, 10 which as assumed is the sixth hundred group, or the one containing the trunk 63, 64, 65. If upon stepping onto the terminals of such trunk a ground is found, indicating the same to be idle, the following 15 circuit is completed: grounded test conductor 63, test brush 18, conductor 66, fourth position contact and side-switch wiper 39, conductor 40, winding of magnet 38 to free pole of battery. The escape magnet by energizing steps the side switch from the fourth to the fifth positions, thus opening the circuit of the magnet 28 and bringing the brushes to rest on the terminals of the idle 20 trunk.

25 Side-switch wipers 7 and 8 extend the calling line over conductors 67 and 68, brushes 20 and 19, to trunk conductors 65 and 64. At the end of conversation a release circuit is closed by placing a ground on test trunk 63.

30 Such circuit leads from grounded trunk conductor 63, test brush 18, conductor 66, fifth position contact and side-switch wiper 51, to the winding of the release magnet 34 and free pole of battery over the path previously traced.

Referring again to the conducting strip 23, it will be seen that the projections 22 are so spaced relative to the length of a long step of the shaft 11 that an even number of 40 steps always places brush 21 in contact with one of said projections. However, if an odd number of steps are taken, brush 21 is brought to rest, at the end of the primary movement, midway between two of the projections 22. Thus if an odd number of impulses are sent, no ground is placed on brush 21 at the end of the primary movement, and the escape magnet subsequently moves the side switch into position 3 to 45 thereby connect the odd digit brushes 15, 16 and 17 with the incoming line. But if an even number of impulses are sent, brush 21 is grounded at the end of the primary movement and the escape magnet subsequently 50 passes the side switch to position 5, thereby connecting the even digit brushes 18, 19 and 20 with the incoming line.

What is claimed is:

1. In a telephone system, a selective 60 switch having two sets of brushes, an incoming line associated with said brushes but normally disconnected therefrom, impulse mechanism and means for operating the same to actuate said brushes, a multiposition auxiliary switch for controlling said

impulse mechanism, and means for variably positioning the auxiliary switch to connect said incoming line to one or the other of said brush sets, dependent upon whether said impulse mechanism receives an even or an odd number of impulses. 70

2. In a telephone system, a switch having groups of terminal contacts therein, said groups being arranged in sections, a set of brushes for each section, an incoming line 75 associated with said sets of brushes but normally disconnected therefrom, impulse operating mechanism for simultaneously moving said brush sets over the terminal groups of their respective sections, a multi-position auxiliary switch and operating means therefor to control said impulse mechanism, and means for variably positioning said auxiliary switch to connect said incoming line to one or another of said brush sets, 80 dependent upon the number of impulses received by said mechanism.

3. In a telephone system, a switch having its terminal bank divided into sections, a set of brushes for each section, a stepping 90 magnet for moving said brush sets simultaneously over their respective sections of the terminal bank, a circuit for the stepping magnet and means for sending a series of impulses over said circuit to operate the 95 magnet, a switch for controlling said circuit, and means for controlling the operation of such switch to render effective one or another of said sets of brushes dependent upon the character of the impulse series sent 100 to said stepping magnet.

4. In a telephone system, a switch having a terminal bank composed of groups of terminals, a brush shaft having a plurality of brush sets fixed thereon, each set being 105 arranged to coöperate with a separate portion of the groups of said bank, an operating circuit having a stepping magnet therein for moving said shaft to position any one of said brush sets in operative relation to any 110 terminal group served by such set, an auxiliary switch operative to control said operating circuit, and means for controlling the operation of said auxiliary switch to render effective the particular set of brushes moved 115 into operative position by the stepping magnet.

5. In a telephone system, a line, a switch having a divided terminal bank, each division consisting of a plurality of groups of 120 terminals, a plurality of sets of brushes mounted on a common shaft, one set for each division of said bank, a primary magnet and an impulse circuit therefor, means for causing a series of impulses to traverse 125 said magnet to position one of said brush sets in operative relation to any group in the division served by such set, a secondary magnet and an impulse circuit therefor, means for causing a series of impulses to 130

traverse the secondary magnet to move a positioned set of brushes over a group of terminals, an auxiliary switch for controlling said impulse circuits, a magnet for actuating such switch, and means for controlling the operation of said last mentioned magnet, said auxiliary switch also being effective to connect said line to one or another of said brush sets, dependent upon the character of the impulse series traversing the primary magnet.

6. In a telephone system, a line, a switch having a bank of terminal groups, a plurality of brush sets, each set assigned to a separate portion of the groups of said bank, a primary magnet and an impulse circuit therefor, means effective to produce a series of impulses in said circuit to cause said magnet to position a set of brushes in operative relation to any terminal group served by such set, a secondary magnet and an impulse circuit therefor, means for causing a series of impulses to traverse said secondary magnet to wipe a positioned set of brushes over a group of terminals, a controlling switch for said impulse circuits with means to actuate the same through a series of successive positions, said switch being arranged to control the secondary impulse circuit in a plurality of such positions, means controlling the actuation of the controlling switch to predetermine its controlling position dependent upon the num-

ber of impulses produced in said primary impulse circuit, and means for connecting said line to one or another of said sets of brushes dependent upon the position assumed by the controlling switch.

7. In a telephone system, a switch having a plurality of brush sets, a line, operating means for giving said brush sets a primary movement, operating means for giving said brush sets a secondary movement, an auxiliary switch with actuating means therefor arranged to assume a plurality of different positions for controlling said secondary operating means, and means including the auxiliary switch for connecting said line to a particular one of said brush sets, dependent upon the controlling position assumed by said auxiliary switch.

8. In a telephone system, a selector switch having a plurality of brushes, impulse operated mechanism for actuating said brushes, and a multiposition side switch for controlling the impulse mechanism and also serving to render one or another of said brushes effective dependent upon the operation of said impulse mechanism, and in accordance with the position assumed by said side switch.

In witness whereof, I hereunto subscribe my name this 8th day of September, A. D. 1917.

CHARLES L. GOODRUM.
